UNITED STATES PATENT OFFICE.

PHILIP W. MOORE, OF EVANSTON, ILLINOIS, ASSIGNOR TO THE P. & M. CO., OF CHICAGO,
ILLINOIS, A CORPORATION OF ILLINOIS.

ANTICREEPER.

1,216,156.

Specification of Letters Patent. Patented Feb. 13, 1917.

Application filed June 16, 1916. Serial No. 103,971.

To all whom it may concern:

Be it known that I, PHILIP W. MOORE, citizen of the United States, residing at Evanston, in the county of Cook and State of Illinois, have invented a certain new and useful Improvement in Anticreepers, of which the following is a full, clear, concise, and exact description.

My invention relates to improvements in anti-creepers or rail anchors, and more particularly to that type of device wherein a rivet, pin or bolt is carried by the anti-creeper and passes through an opening in the web of the rail as an aid in securing the anti-creeper in position. In such devices the tie-abutting flange has been located on that side of the center line of the rail base adjacent to the portion provided with the pin or rivet. The creeping thrust of the rail under these conditions tends to skew the anti-creeper and force it from its proper position on the rail developing stresses which tend to tear off the rivet.

The object of the present invention is to provide an anti-creeper of this general type in which this difficulty is overcome.

In illustrating the invention, I have shown two forms of anti-creepers in each of which the tie-abutting flange is located 30 near the opposite side of the rail base; that is, on the side of the anchor away from the side that carries the rivet. With this arrangement of parts, the skewing action is reversed, and the tendency to tear off the rivet is considerably lessened. Other advantages are also obtained, as will be apparent from the following description:

Figure 1 of the drawings is a top plan view of one form of anti-creeper, the rail 40 being broken away in part.

Fig. 2 is a side elevation thereof.

Fig. 3 is a rear elevation thereof, the rail being shown in section.

Fig. 4 is a top plan view of a second 45 form of anti-creeper shown applied to the rail.

Fig. 5 is a side elevation thereof; and

Fig. 6 is a rear elevation thereof with the rail shown in section.

50 The first form of rail anchor consists of a base member 1 extending beneath the rail base from one side to the other and having integral jaws 2, 3 at the sides of the rail base, each of which is arranged to fit 55 over the base flange. The jaw 3 is pro-

vided with a vertical extension 4 adjacent to the web of the rail and carries a suitable fastening device, such as a pin, rivet or bolt 5, which passes through an opening in the web of the rail 6. The rail is supported 60 on the usual cross tie 7 against which a downwardly extending flange 8 bears. Said flange is located at the left of the base member as shown in Fig. 3, whereas the vertical extension 4 and the pin 5 are connected with 65 the right hand side thereof through the jaw 3. In other words, the pin supporting element and the flange are connected to opposite sides of the base plate.

When the rail creeps, the anchor tends to 70 skew in such a direction that the jaws 2 and 3 increase their grip on the rail base. There is very little tendency to tear out the rivet in view of the fact that said skewing is resisted primarily by said jaws and the 75 base plate instead of being resisted almost wholly by the vertical extension 4.

The rail anchor may be made as a casting of suitable metal, such as malleable iron for example, or it may be stamped from a steel 80 plate and bent to shape, or it may be otherwise formed. In applying it to the rail base, it is turned at such an angle as to provide the maximum possible distance between the jaws 2 and 3, after which it is swung to the 85 position shown in Fig. 1, and the rivet 5 passed through the opening in the web of the rail. The opening in the web may be drilled by using the opening in the rail anchor as a templet. The type of fastening 90 means shown in Figs. 1 to 3 is a rivet which has preferably a driving fit in the opening in the rail, although other fastening means may obviously be employed. Furthermore, the opening in the rail need not necessarily 95 be in the vertical web thereof, but may be otherwise located. The fastening device prevents skewing of the rail in a direction to decrease the effectiveness of the grip of the rail anchor on the rail base.

100 In the form of anchor shown in Figs. 4, 5 and 6, the base member has the form of a transverse bar 10 having a jaw 11 at one end and an up-turned extension 12 at the other. The jaw has a vertical arm 11' which carries a suitable fastening device which is illustrated as a bolt 13, but which may be a pin, rivet, or other suitable equivalent means for securing said extension to the web of the rail. A tie-abutting flange 14 is 110

arranged at one side of the central axis of the rail as in the previous construction.

In applying the rail anchor to the rail base, the jaw 11 is applied to one side thereof and the extension 12 is then bent over the opposite side of the rail base as far as possible by hammer blows, thus forming a second jaw. The creeping tendency of the rail tends to skew the anchor, but the skewing is resisted by the jaws on opposite sides whereby there is little tendency to tear out the rivet.

This form of rail anchor may be conveniently stamped from steel, although it may also be made as a malleable casting or of other suitable material.

The invention is not to be limited to the embodiments thereof described, as various other forms may be devised which fall within the scope of the appended claims.

Having thus described my invention, what I claim as new and desire to secure by Letters Patent of the United States is:

1. An anti-creeper comprising a member beneath the rail base, an integral jaw thereon fitting one side of the rail base and carrying a locking pin, and a tie abutting extension on said member located toward the other side of said rail base to cause said anchor to skew.

2. An anti-creeper comprising a member beneath the rail base, an integral jaw thereon fitting one side of the rail base and carrying a locking pin, a tie abutting extension

on said member located toward the other side of said rail base to cause said anchor to skew, and a second jaw on said member on the side adjacent to said tie-abutting flange, said jaws increasing their grip on the rail base when said anchor skews.

3. An anti-creeper comprising a member which extends beneath the rail base from one side to the other, a jaw at each end thereof, a downwardly extending projection on said member near one of said jaws, the other of said jaws having an opening and means passing through said opening and through an aligned opening in the rail to aid in securing said anchor in position.

4. A rail anchor comprising means for gripping opposite sides of the rail base, a tie-abutting flange arranged at one side of the central axis of the rail to cause said anchor to skew, and means on said anchor passing through an opening in said rail to positively lock the rail anchor thereto.

5. A rail anchor comprising a base member, means at opposite sides thereof engaging the sides of the rail base, an extension on one of said means arranged adjacent to the vertical web of the rail, fastening means cooperating with said extension and said web to secure the anchor to the rail, and a tie-abutting flange on said base member on the side thereof opposite said extension.

In witness whereof, I hereunto subscribe my name this 9th day of June A. D., 1916.

PHILIP W. MOORE.
